UNITED STATES PATENT OFFICE.

ABNER B. POWERS, OF DENVER, COLORADO.

DESIGN FOR A LAMP-CHIMNEY.

SPECIFICATION forming part of Design No. 29,671, dated November 15, 1898.

Application filed September 12, 1898. Serial No. 690,805. Term of patent 3½ years.

To all whom it may concern:

Be it known that I, ABNER B. POWERS, a citizen of the United States, residing at Denver, in the county of Arapahoe and State of Colorado, have invented and produced a new and original Design for Lamp-Chimneys; and I do declare the following to be a full, clear, and exact description of the invention, such as will enable others skilled in the art to which it appertains to make and use the same, reference being had to the accompanying drawings, forming a part of this specification, in which similar letters of reference indicate corresponding parts in all the figures.

Figure 1 is a plan view of my new design for a lamp-chimney. Fig. 2 is a vertical section of same. Fig. 3 is a cross-section along line *a a* of Fig. 1.

As shown in the drawings, the leading and material features of my new lamp-chimney consist of the convex portions A and the lugs B. The convex portions consist of a series of projections or corrugations divided longitudinally, as shown. A high degree of ornamentation can thus be derived, as well as utility.

Having thus described my invention, what I claim as new, and desire to secure by Letters Patent, is—

The design for a lamp-chimney, as herein shown and described.

ABNER B. POWERS.
